SEGMENT DELIVERING

Walter L. Gibboney, Denver, Colo.

Application July 21, 1943, Serial No. 495,669

8 Claims. (Cl. 107—21)

1

This invention relates to segmenting and wrapping apparatus adapted to progressively cut off fractions of uniform size and shape from a mould or block of scissile material and individually wrap the separated fractions, and more particularly to apparatus of such type specifically arranged to size and wrap units of frozen or semi-frozen confections, such as ice creams and ices, and has as an object to provide an improved arrangement and combination of elements constituting such an apparatus.

A further object of the invention is to provide an improved combination of segmenting means in cooperation with wrapping means for the production of individually wrapped fractions of a mould or block of ice cream or similar material.

A further object of the invention is to provide improved means, in a unitary combination, for feeding frozen material, such as ice cream, progressively through sectioning and wrapping means.

A further object of the invention is to provide an improved table wherewith frozen material, such as ice cream, may be progressively fed to and through sectioning and wrapping means without undesirable tendency of the material to stick or adhere.

A further object of the invention is to provide improved means for regularly and intermittently advancing a block or mould of material relative to a continuously rotating cutter for the severance of fractions of uniform size from said block or mould.

A further object of the invention is to provide, in a compact unitary combination, ice cream sizing and wrapping apparatus that is rapid and efficient in operation, characterized by high capacity at low operating cost, which minimizes handling of the material treated thereby, which, because of the progressive and rapid cycle of its operations, may be utilized in areas of normal temperature without adverse effect on the frozen material passed therethrough, which is simple of semi-automatic functioning, and which is long-lived in use with a minimum of maintenance.

With the foregoing principal, and other more detailed, objects in view, my invention consists in the construction, arrangement, and combination of elements hereinafter set forth, pointed out in my claims, and illustrated by the accompanying drawings, in which—

Figure 1 is a vertical section taken longitudinally and centrally through a typical arrangement of elements constituting a preferred embodiment of the invention. Figure 2 is a frag-

2

mentary plan view, partly in section and on an enlarged scale, taken substantially on the indicated line 2—2 of Figure 1. Figure 3 is a fragmentary, detail section, on the same scale as Figure 2, taken on the indicated line 3—3 of Figure 1. Figure 4 is a view of the left half of the apparatus shown in Figure 1 with movable elements of the assembly at an opposite limit of their range of actuation. Figure 5 is an elevation, on an enlarged scale, of a pressure plate and associated elements employed in the improved apparatus. Figures 6, 7 and 8 are similar, somewhat diagrammatic, elevations of intermittent feed means advantageously employed in the improved apparatus; the various views illustrating various operative positions of such feed means.

In the manufacture of frozen and semi-frozen confections, such as ice creams and the like, it is convenient and economical to mould, set, and temper the product in the form of relatively large, rectangular blocks or bricks, subsequently divide the moulded units into fractions of a uniform size suitable for individual consumption, and finally separately wrap the fractions for packing, storage, sale, and convenience of the consumer. The character and nature of the product are well known to be such as to introduce factors adversely affecting the cutting, feeding, and wrapping thereof by means of conventional apparatus, and the instant invention is directed to the improvement and alteration of hitherto known means and devices in a manner to adapt such agencies for successful use in the field and for the purposes specified.

35 In the construction of the improvement as shown, the numeral 10 designates a suitable, horizontally-disposed bench or table wherewith the various elements and assemblies of the apparatus are associated. The table 10 is preferably elevated, as by means of suitable supports 11, to bring the apparatus carried thereby to a height convenient for an operator, and the form, size, and specific construction of the table 10 may be such as, within wide limits, will serve its purpose 45 in the invention.

Carried by and rising above one end of the table 10, a segmenting assembly is positioned to initially receive and automatically fraction the moulds or blocks of material to be wrapped. The segmenting assembly includes spaced, parallel frame members 12 and 13 fixed at their lower ends to and rising perpendicularly above the table 10 in spaced relation longitudinally thereof, and the said frame members are spaced apart a distance somewhat in excess of the length of the mould or

block of material to be worked upon. Upper ends of the frame members 12 and 13 are preferably extended laterally of the table 10 to form brackets whereon a storage shelf 14 is supported and fixed with its upper surface disposed in a horizontal plane parallel with and above that of the table 10. The shelf 14 is adapted to receive and support within convenient reach of an operator a plurality of moulds or blocks 15 of the material to be worked upon, and for such purpose said shelf preferably has a length greater than that of the blocks 15 and a width such as will accommodate a number of such blocks at one time. Since the material to be treated by the improved apparatus is in frozen or semi-frozen condition, the shelf 14 is arranged or adapted to protect the temperature condition of the material, a cooling chamber 14' associated with and beneath said shelf in operative communication through an inlet 16 and outlet 17 with a system for the circulation of cooling fluid being illustrated as one convenient and conventional means for such purpose. Fixed to corresponding lower portions of the frame members 12 and 13 and supported thereby in bridging relation therebetween and in spaced, parallel relation above and longitudinally of the table 10, an upwardly-opening, U-shaped trough 18 is positioned to receive and hold a block 15 of the material to be worked upon. The trough 18 has a width of opening slightly in excess of the width of a block 15, a length in excess of that of such block, a height of side wall preferably somewhat greater than the block thickness, is open at each end, and is preferably formed from suitable material, such as metal, which may be readily cleaned and sterilized, which is a good conductor of heat, and which will not react to or with the material comprised within the blocks 15. The trough 18 is formed with a vertically-opening slot 18' centrally and longitudinally intersecting its bottom web throughout the major portion of the trough length and preferably stopping short of intersection through the trough ends, and said trough is arranged, as by means of chambers or compartments 19, associated with and preferably beneath the trough bottom in operative communication through inlet and outlet lines 20 and 21 with a system for the circulation of heated fluid, such as steam or air, to be heated to that degree which will obviate any tendency of the frozen or semi-frozen material to adhere to and stick within said trough. The circulating system represented by the lines 20 and 21 may be served from any suitable source or supply of heated fluid, and while the compartments 19 are illustrated as formed integrally with the trough bottom, it is to be understood that such showing is merely typical and representative of any means suitable for elevating the temperature of the trough bottom and side walls through flow of heated fluid adjacent thereto.

Mounted for rotation in and extending between lower portions of the frame members 12 and 13, parallel with and spaced centrally beneath the trough 18, a steep-pitch screw 22 is operatively disposed with one of its ends extending outwardly through and beyond the frame member 12 at the end of the table 10. Rotation of the screw 22 serves to feed a block 15 longitudinally along the trough 18, and for such purpose a pressure plate 23 is loosely and slidably fitted within and in obstructing relation transversely of the trough 18, said plate 23 being formed with a perpendicularly-related, central web 23' on its sur-

face adjacent the frame member 12 and in position to register with the slot 18' of said trough, through which slot a lower extension of said web is received to position and guide the plate 23 relative to the trough 18. The plate 23 is adapted to be automatically fed along and from the outer toward the inner end of the trough 18 through the agency of the screw 22, and to be manually returned from the inner to the outer end of said trough, for which purpose means of the type illustrated in Figure 5 are provided for selectively engaging said plate in operative relation with said screw. The means shown in Figure 5 include a handled jaw member 24 fixed at its inner jaw end to the lower end of the downward extension of the web 23' above the screw 22 in position to extend laterally of and outwardly beyond the trough 18. The inner end of the member 24 is formed with an arcuate notch 24' adapted to conform to the curvature of and closely overlie the upper portion of the screw 22, and a suitable hinge boss formed on said member 24 at some distance outwardly from its inner end cooperates with a similar boss on a complementary handled jaw member 25 to hingedly interconnect said members 24 and 25 for relative actuation in a vertical plane with the member 25 beneath the member 24. The inner, jaw end of the member 25 underlies the corresponding end of the member 24 and is formed with an arcuate notch 25' adapted to conform to the curvature of and closely underlie the lower portion of the screw 22, said notches 24' and 25' thus cooperating to substantially embrace said screw, and a stud 26 is fixed within and rises radially from the notch 25' to engage within the thread notch or groove of the screw 22 when the handle portions of the members 24 and 25 are urged apart, as by means of a spring 27 engaging for such purpose therebetween. With the arrangement shown, it is apparent that separation of the handled portions of the members 24 and 25 operates to engage the stud 26 with the thread of the screw 22, so that rotation of said screw in the proper direction will feed the entire assembly, including the plate 23, longitudinally along the trough 18, and so that when the handle portions of the members 24 and 25 are gripped and drawn together against the pressure of the spring 27, the stud 26 is retracted from its engagement with the screw 22 and the assembly may then be manually moved in either direction longitudinally of the trough; release of the handle portions of the members 24 and 25 serving to again establish automatic feeding relation between the screw 22 and plate 23.

Journaled for rotation in and extending through intermediate portions of the frame members 12 and 13, a shaft 28 is mounted between the shelf 14 and trough 18 in alignment with and spaced parallelism above the screw 22, and the end of said shaft projecting outwardly beyond the frame member 12 is fixed in and carries a belt pulley 29, or equivalent means, whereby said shaft 28 may be connected, as by means of a belt 30, with an electric motor (not shown) for rotation thereof. The end of the screw 22 projecting beyond the frame member 12 carries a pinion 31 fixed thereto beneath the pulley 29, and said pinion operatively meshes with a gear 32 therebeneath and mounted for free rotation on and above a stub shaft 33 fixed in parallel, spaced relation with and beneath the adjacent end of the screw 22. A concentric boss is provided on the outer face of the gear 32 and is peripherally

formed as a series of identical, equally-spaced, ratchet teeth 34 in this instance four in number. An arm 35 is pivoted at one end on and extends radially from the stub shaft 33 to pivotal connection of its other end, beyond the radius of the gear 32, with the lower end of a pitman or link 36 which connects at its upper end with a crank pin 37 eccentrically carried by and projecting from the outer face of the pulley 29. The arm 35 operatively carries a detent 38 arranged to ratchet over the teeth 34 during downward oscillation of said arm and to successively engage against said teeth and rotate the gear 32 during upward oscillation of the arm, and the ratio of the pinion 31 to the gear 32, the number of teeth 34, the effective length of the arm 35, and eccentricity of the crank pin 37 are all so adjusted and correlated so as to impart to the screw 22 that degree of rotation resulting in the desired linear travel of the plate 23 along its trough 18 for each complete revolution of the pulley 29 and shaft 28.

The shaft 28 projects at its inner end beyond the frame member 13 to fixedly engage with and operatively support a rotatable knife or cutter 39 thus disposed for actuation in a plane perpendicular to said shaft 28 and hence perpendicular to the longitudinal axis of the trough 18. The knife 39 may be of any specific form and construction suited to its purpose, a thin steel blade of the general form illustrated in Figure 3 and having a sharpened, spirally-arranged cutting edge, having been found satisfactory in practice. The knife 39 has an operative length radially of the shaft 28 somewhat greater than the distance between said shaft and the bottom of the trough 18, and said knife is disposed for rotation through an orbit closely adjacent the inner end of the trough 18. As will be apparent, the knife is arranged to rotate with and at the same speed as the pulley 29, and the angular relation between the cutting edge of said knife and the position of the crank pin 37 is such as to sweep the cutting edge of said knife across the inner end of the trough 18 when the arm 35 is moving downwardly in ratcheting relation of its detent relative to the ratchet teeth 34, which arrangement provides for cutting engagement of said knife with a block 15 while the screw 22 is at rest and the block 15 consequently not in motion, while actuation of said screw is had for feeding of the block 15 along the trough 18 while said knife traverses that portion of its orbit wherein it is out of cutting relation with said block.

To limit travel of the plate 23 inwardly along the trough 18, it is convenient to provide said plate with an upwardly and laterally extended finger 40 disposed for engagement, when said plate approaches the inner limit of its range of travel, with the trigger 41 of a switch 42 connected in controlling relation with the circuit serving the motor which actuates the pulley 29.

The apparatus thus far described is a complete segmenting or fractioning device and is operable to successively receive the blocks 15, intermittently feed said blocks uniform distances along the trough 18, and automatically sever fractions of uniform size from said blocks. Since the blocks 15 may vary somewhat in width and the trough 18 is slightly wider than said blocks, a trimming blade 43 is preferably vertically disposed in fixed relation inwardly and adjacent the end of one side wall of the trough 18, the action of said blade being to urge the block 15 against the opposite trough side wall and trim the adja-

cent side of said block for the production of block fractions of uniform length.

Fractions 15' cut from a block 15 are delivered to and slidably received in a U-shaped trough 44 of considerable length similar to the trough 18 and fixedly supported from and above the table 10 in end registration and longitudinal alignment with said trough 18, the bottom of the trough 44 being coplanar with that of the trough 18. The adjacent ends of the trough 18 and 44 are spaced apart a minimum distance sufficient to provide clearance for the knife 39 as the latter revolves, and the trough 44 is suitably arranged, as by means of chambers or compartments 45 adjacent underlying the trough bottom and in operative communication through inlets and outlets 46 and 47, respectively, with a system for the circulation of heated fluid, such as steam or air, to be heated to such degree as will obviate any tendency of the fractions 15' to adhere to or stick within said trough. At the end of the trough 44 adjacent the trough 18, an inclined chute 48 opens through a side wall of the trough and cooperates with the bottom of the latter to receive and conduct away from said trough 44 trimmings removed from a block 15 by the blade 43. Fractions 15' cut from a block 15 are received in the trough 44 and progressively moved therewith along as the block 15 is intermittently fed along its trough 18, but feeding of the fractions 15' outwardly through the other end of the trough 44 is designedly a manual function and is accomplished by the operator by means of a blade or paddle (not shown) which is inserted between adjacent fractions 15' for the application of pressure to move those fractions remote from the knife 39 along the trough 44 and outwardly of and past the end of said trough remote from the trough 18. Fixed to the upper end of a stem 49 mounted for vertical reciprocation in and through suitable guides 50 fixedly related with the table 10, a U-shaped transfer tray 51, conforming in cross section with the trough 44, is mounted for end registration in closely spaced relation with the end of the trough 44 remote from the trough 18, at times, and for altitudinal reciprocation between coplanar relation of its bottom with that of the trough 44 and a lower plane parallel with that of the trough bottom. The tray 51 has a length approximately twice the width of a fraction 15', and is arranged to cooperate, when at the upper limit of its range of reciprocation as shown in Figure 1, with a stop plate 52 fixedly supported in position to obstruct and divide the channel through the tray 51 so that only one of the fractions 15' pushed outwardly along the trough 44 may be received at one time by the tray 51. To obviate any tendency of a fraction 15' to stick or adhere to the plate 52, a branch 53 from the heated fluid circulating system is arranged for jet discharge against the surface of the plate 52 opposite to that engaged by a fraction 15'. In its lowermost position the tray 51 is adapted for end registration with a U-shaped trough 54 fixedly supported above the table 10 in longitudinal alignment with the trough 44 and with its bottom surface in a plane parallel with that of the trough 44 bottom surface and at a level sufficiently lower as to permit a fraction 15' to pass freely beneath the lower margin of the plate 52, as is clearly shown in Figure 4. It is the function of the tray 51 to successively receive fractions 15' and automatically position the individual fractions constituting its charge for transfer to the trough 54, for which purpose said tray 51 is ar-

ranged for automatic, repetitive actuation between the limits of its range of travel. Any arrangement of means suitable to the end desired may be employed to operatively associate the tray 51 with a source of power, simple means for the purpose being diagrammatically illustrated as comprising a power-driven shaft 55, a cam 56, fixedly associated with said shaft, a lever 57, mounted for oscillation through a vertical arc and operatively engaging with said cam, a slide 10, bar 58, mounted for rectilinear reciprocation in a horizontal plane and connected for actuation with the lever 57, and a bell-crank 59, whereof one of the arms operatively engages with the stem 49 supporting the tray 51 and the other arm is provided with an end-opening notch disposed for cooperation with a pin carried by the slide bar 58. The cam track of the element 56 is so arranged as to hold the lever 57 at one limit of its range of oscillation for a brief time, then shift said lever to the opposite end of its range of oscillation and hold said lever at such limit for a brief time period, and subsequently return said lever to its original position, which action operates through the slide bar 58 and bell-crank 59 to raise and lower the tray 51 between its limiting positions coplanar with the bottoms of the troughs 44 and 54, and to briefly hold said tray at each of said limiting positions for transfer of fractions 15' to and from said tray.

Means synchronized with the travel of the tray 51 are provided for automatically shifting a fraction 15' from said tray and to the trough 54 when the tray is at the lower limit of its travel, said means comprising a horizontally-disposed stem 60, mounted for reciprocation beneath the trough 54 in suitable supports fixedly upstanding from the table 10, said stem being provided with a head or plunger at its end adjacent the tray 51 so positioned as to register for engagement against the adjacent side of a fraction 15' carried by said tray when in its lowermost position. Actuation of the stem 60 in properly timed relation with the travel of the tray 51 is conveniently had through the agency of a link 61 pivoted at a point below the slide bar 58 for oscillation through a vertical arc extending past and above said slide bar, said link operatively engaging at its upper end with the stem 60 and being provided with a radially-opening jaw 62 disposed for engagement at times with a pin projecting laterally from and in fixed relation with the slide bar 58. As will be apparent from the showing of Figures 1 and 4, rotation of the shaft 55 operates through the means and connections hereinabove described to lower the tray 51 into coplanar relation with the trough 54, subsequently project the stem 60 across the lowered tray for transfer of a fraction 15' from said tray to said trough, then retract the stem 60 into clearing relation with the tray 51, and finally elevate said tray into coplanar relation with the trough 44 in position to receive another charge.

The trough 54 is the feed-way of typical wrapping apparatus conventionally and diagrammatically represented in Figures 1 and 4. The wrapping apparatus may be of any desired or suitable specific construction and operative arrangement, and is represented as including standards 63 rising from the table 10 on opposite sides of the trough 54 to operatively support a roll 64 of suitable wrapping material, such as waxed or parchment paper, or the like, wherefrom the web 65 extends through suitable guide and tensioning means and through a series of paired rollers 66.

to perpendicularly-intersecting relation with the bottom of the trough 54 in obstructing position across said trough where it is disposed to be engaged by a fraction 15' moved along said trough by the stem 60. As it passes through the series of paired rollers 66, the web 65 is automatically divided, as by means of a cutter blade 67 fixed longitudinally of and extending radially from one of said rollers for periodic registration with a groove formed longitudinally of the associated roller surface, into sections of uniform length suitable for the wrapping of a fraction 15', and means, such as movable fingers, inclined and curved surfaces, and the like, are operatively associated with the trough 54 adjacent and along the path traversed by a fraction 15' moving under the influence of the stem 60, so that the section of the web 65 engaged by a fraction 15' is wrapped and securely folded about such fraction in a common and well-known manner. Since the elements and agencies operable to actually fold and wrap the enveloping material about a fraction 15' are old in the art and in themselves form no part of the present invention, any showing or specific description thereof is omitted. The operating elements of the wrapping apparatus are power driven, as by means of a belt 68, or otherwise, in suitable correlation with the rotation of the shaft 55, to provide that a severed section of the web 65 is disposed in obstructing relation across the trough 54 in position to be engaged by and wrapped about a fraction 15' as the latter is moved from the tray 51 and along the trough 54 by the stem 60.

35. The wrapped fractions 15' may be removed or discharged from the trough 54 in any desired or convenient manner, collected for storage in suitable coolers, or packed in suitable containers for storage and transportation, the wrapped units produced by the improved apparatus being ready for marketing.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

50. I claim as my invention—
1. In apparatus productive of a continuing succession of like, uniform-size block fractions and characterized by altitudinally-reciprocable means for individually delivering said fractions to subsequent operations, means for the selective transfer of said fractions to said delivering means, said transfer means comprising a straight, horizontally-disposed trough adapted to slidably accommodate a succession of said fractions, an open input end on said trough sized and positioned to slidably receive the block fraction output, and an open output end on said trough in registration with said reciprocable delivering means at one limit of its altitudinal range.

65. 2. In apparatus automatically productive of a continuing succession of like, uniform-size blocks of frozen and semi-frozen material and characterized by automatically-cyclic, altitudinally-reciprocable means for individually delivering said fractions to subsequent operations, means for the selective transfer of said fractions to said delivering means, said transfer means comprising a straight, elongate, horizontally-disposed trough adapted to slidably accommodate a succession of said fractions, means for moderately heating

the length of said trough, an open input end on said trough sized and positioned to slidably receive the block fraction output, and an open output end on said trough in registration with said reciprocable means at one limit of its altitudinal range.

3. Apparatus as set forth in claim 2, wherein the outlet end of said trough registers with the upper, limiting position of a fraction-accommodating tray element altitudinally reciprocable between said upper position and end registration with a lower trough constituting a feed-way.

4. Apparatus as set forth in claim 2, wherein the fraction-delivering means includes a feed-way aligned with and spaced endwise from and below the trough, and a fraction-accommodating tray element is disposed for power actuation between upper and lower limiting positions represented by end registration of said tray with said trough and feed-way respectively.

5. In apparatus of the character described having a horizontally-disposed, open-ended, heated trough adapted to slidably accommodate uniform-sized fractions cut from a block of gelid material, fraction receiving and delivering means adjacent the output end of said trough and comprising a feed-way in end spaced, aligned, altitudinally offset relation with and below said first trough, a power-actuated transfer tray altitudinally-reciprocable between alternate end registration with said troughs, and means operable as an incident of tray reciprocation to transfer a charge from said tray to said feed-way.

6. Apparatus as set forth in claim 5, wherein

said transfer tray cooperates, when in end registration with the heated trough, with a fixed stop plate disposed to transversely divide and obstruct the passage through said tray.

5. Apparatus as set forth in claim 5, wherein the means for actuating the transfer tray is arranged to hold said tray at rest for a brief time at each limit of its range of travel.

8. Apparatus as set forth in claim 5, wherein the means for transferring a charge from the transfer tray to the feed-way includes a stem in spaced, parallel alignment beneath the heated trough and axially reciprocable into and out of extension across said tray when the latter is in end registration with the feed-way.
